Primary Examiner — Mimosa De

(74) Attorney, Agent, or Firm — Thomas P. O'Connell;
O'Connell Law Firm(57) **CLAIM**

The ornamental design for a task chair, as shown and described.

DESCRIPTION

FIG. 1 is a perspective view of a task chair showing my new design;

FIG. 2 is a view in front elevation thereof;

FIG. 3 is a view in right side elevation thereof with the view in left side elevation being a mirror image of the view in right side elevation;

FIG. 4 is a top plan view thereof;

FIG. 5 is a bottom plan view thereof; and,

FIG. 6 is a view in rear elevation thereof.

The broken lines in the drawings represent unclaimed features of the task chair and form no part of the claimed design.
